UNITED STATES PATENT OFFICE.

JULIUS FRIEDRICH CHARLES JÜRGENS, OF ALTONA, GERMANY.

GAS-COCK HAVING IGNITING-TUBE.

SPECIFICATION forming part of Letters Patent No. 627,121, dated June 20, 1899.

Application filed January 18, 1898. Serial No. 667,107. (No model.)

To all whom it may concern:

Be it known that I, JULIUS FRIEDRICH CHARLES JÜRGENS, a subject of the King of Prussia, German Emperor, residing at Altona, Germany, have invented certain new and useful Improvements in Gas-Cocks Having Igniting-Tubes, of which the following is a specification.

This invention relates to a gas-cock having an igniting-pipe and provided with improved means for turning the cock-plug back after the ignition of the main flame by such pipe has been effected.

In the accompanying drawings, Figure 1 is a front elevation of a Bunsen burner provided with my improvement. Figs. 2, 3, and 4 are vertical sections showing the gas-cock in three different positions—viz., (a) with the igniting-pipe opened and the main pipe partly opened, (b) with the igniting-pipe closed and the main pipe completely opened, and (c) with both the igniting-pipe and the main pipe closed. Fig. 5 shows the gas-cock in horizontal section, and Fig. 6 is a ring for effecting the automatic closing of the gas-cock.

The igniting-pipe *b* branches off in the usual manner from the cock-casing *a*. This igniting-pipe may be either an ordinary pilot-flame pipe or it may be an ordinary igniting-pipe provided with an igniting-body—such, for example, as spongy platinum. The igniting-pipe communicates, by means of a small lateral hole *c*, with the bore *d* of the cock-plug *f*, so that the passage for the supply of gas may take place through the igniting-pipe and the partially-open main pipe, Fig. 2, or through the main pipe alone, Fig. 3, to the burner, or may be completely cut off, Fig. 4. In order to obviate a further operation of the plug by hand for the purpose of cutting off the supply of gas to the igniting-pipe after the main jet has been ignited, the casing *a* is provided at its front end with a short recess *g*, in which engages the pin *h* of a ring *i*, which is loosely mounted on the plug, Fig. 5, so that it can freely rotate on the plug in either direction. This ring is also provided on its front face with a recess *k*, in which works a pin *n*, fixed to a lever *m*, rigidly mounted upon the end of the plug *f*, and from the opposite ends of which rings *q* and *r* are suspended.

By means of a spring *p*, which is attached at one end to a ring *o* of the burner-casing

and at the other end to the ring *i*, or by means of a weight attached to the ring *i*, the said ring *i* has a constant tendency to turn and bring its pin *h* to bear against the right-hand shoulder or stop of the recess *g*.

When the main flame has to be ignited, the ring *q* is pulled to rotate the plug *f* by lever *m* and cause the pin *n* to strike the left-hand shoulder or stop of the recess *k*, Fig. 1. On further pulling the ring *q* the ring *i* will be moved also against the action of the spring *p*, which will be placed in tension. This will continue until the pin *h* strikes against the left-hand shoulder or stop of the recess *g*. In this position (see dotted line A A of Fig. 1 and the sectional view, Fig. 2) the bore *c* of the plug coincides with the branch passage *b*, so that ignition of the main supply of gas can be effected. When this has been done, the ring *q* is released, whereupon the spring *p* rotates the ring *i* freely on plug *f* toward the right until the pin *h* strikes the upper end of the short recess *g*. During this short travel of the ring it will have taken the plug *f* along by means of the engagement of the end of recess *k* with pin *n* of lever *m*, and thus the plug will be turned a short distance back to close the branch passage, but leave the main passage open, Fig. 3. In order to extinguish the flame, it is sufficient to pull the ring *r* so that the pin *n* passes through the recess *k* without taking ring *i* along and until the pin *n* comes in contact with the right-hand shoulder of the recess *k*. (See dotted line B B of Fig. 1 and the sectional view, Fig. 4.) The motion thus imparted to the plug *f* by lever *m* will have closed the main gas-passage and extinguished the flame.

What I claim is—

A gas-cock composed of a recessed casing, a plug having a main and a branch duct, a spring-actuated recessed ring rotatable upon the plug and provided with a stop-pin adapted to engage the recess of the casing, and a plug-operating lever having a pin that engages the recess of the ring, substantially as specified.

Signed at Hamburg, Germany, this 4th day of January, A. D. 1898.

JULIUS FRIEDRICH CHARLES JÜRGENS.
